[57] CLAIM

The ornamental design for an infusion pump, as shown and described.

DESCRIPTION

FIG. 1 is a front, side perspective view of the infusion pump of the present invention;

FIG. 2 is a top elevational view of the infusion pump of the present invention;

FIG. 3 is a side elevational view of the infusion pump of the present invention;

FIG. 4 is a front side elevational view of the infusion pump of the present invention;

FIG. 5 is a back side elevational view of the infusion pump of the present invention;

FIG. 6 is a bottom plan view of the infusion pump of the present invention; and,

FIG. 7 is a side elevational view of the infusion pump of the present invention, illustrating the side opposite that of the side illustrated in FIG. 3.

*Fig. 1**Fig. 2**Fig. 3**Fig. 4**Fig. 5**Fig. 6**Fig. 7*
